UNITED STATES PATENT OFFICE.

HENRY ALBIN REGEN, OF DENVER, COLORADO.

ROTARY ENGINE.

1,059,637.

Specification of Letters Patent.

Patented Apr. 22, 1913.

Application filed April 10, 1912. Serial No. 689,851.

To all whom it may concern:

Be it known that I, HENRY A. REGEN, citizen of the United States of America, residing at Denver, in the county of Denver 5 and State of Colorado, have invented certain new and useful Improvements in Rotary Engines, of which the following is a specification.

My invention relates to rotary engines of 10 the type in which the motive force is derived from the action of steam or other motive fluid admitted between a piston on the rotor and a relatively stationary abutment which periodically moves into the path 15 thereof.

In the ordinary construction of engines of 20 this type either the piston or the abutment reciprocates to enable the one to pass the other during the rotary movement of the element of which the piston forms part, and it is the principal object of the present invention to provide an engine of very simple construction in which all the moving parts 25 rotate in the performance of their respective functions.

An embodiment of my invention has been shown in the accompanying drawings in the various views of which like parts are similarly designated and in which,

30 Figure 1 represents a vertical section through the engine, in the plane of the axis of rotation of its rotor, Fig. 2, a section taken along the line 2—2, Fig. 1, Fig. 3, an end-elevation of the engine, Fig. 4, a horizontal section taken along the line 4—4, Fig. 3, and Figs. 5, 6 and 7 sections similar to that shown in Fig. 2, illustrating different positions of the operative parts of the engine.

40 Referring more specifically to the drawings, my improved engine consists of a housing 2, the cylindrical body portion 3 of which is supported upon an integral base 4. The interior of the body portion is by means 45 of a concentric wall 5, divided into an annular piston-chamber 6 and a steam-chamber 7 which by means of a conduit 8 secured in the end-wall of the housing, connects with a source of motive fluid. The housing 2 is 50 furthermore provided with an annular abutment chamber 9 in which an arcuate abutment 10, hereinafter to be more fully described, has a rotary movement.

The abutment chamber 9 whose diameter 55 is less than that of the piston chamber, is

placed in intersecting relation to the latter whereby it is divided into two arcuate sections, one of which extends through an internal enlargement 12 of the dividing wall 5, while the other extends through the engine-base 4. 60

A valve-chamber formed in the interior enlargement of the dividing wall, in communication with the steam-chamber 7, is designed to be occupied by a rotary valve 13, 65 the stem 14 of which projects through a combined stuffing-box and bearing 15 which forms part of a screw-plug 16 by which the open end of the valve-chamber is normally closed. 70

The valve 13 is composed of a hollow cylinder, the interior of which is in continuous communication with the steam-chamber by an opening in its end, and it is provided with a longitudinal slot 17 through which 75 the steam is periodically admitted into a port 18 which by means of a channel 19 connects with an outlet-port 20 in the piston-chamber 6.

The port 20 is located at the lower portion 80 of the piston chamber intermediate the entrances to the upper section of the abutment chamber, in a line passing through the centers of the two annular chambers, and a port 21 located in the same line at the upper 85 portion of the piston chamber serves to exhaust the spent motive fluid therefrom into a conduit 22.

The rotor of the engine is composed of a disk 23 fixedly secured upon the engine shaft 90 24 which is rotatably supported in an axial bore of the enlargement 12 of the dividing wall 5 and in bearings 25 and 26 formed integral with the end-wall of the housing and with a head 27 which normally closes the 95 opposite, open end of the same.

The disk 23 is movably disposed between the end-wall 28 of the steam-chest defined by the circular wall 5 and the inner surface of the head 27, and it carries a piston 29 100 100 which, projecting laterally from its peripheral portion, is movably fitted between the circular inner and outer walls of the annular piston chamber 6.

The rotary abutment 10 which is fitted to 105 move within the abutment-chamber 9, projects laterally from a disk 30 which being movably disposed in a recess at the end of the housing opposite to that closed by the head 27, is by means of an integral shaft 110

32 rotatably supported in a bearing 31 on a plate 32 which normally closes the recess in which the disk has its movement.

The corresponding ends of the valve stem 14 and the two shafts 24 and 32 are connected to move in unison at equal rates of speed by means of a train of gear-wheels 33, best shown in Fig. 3 of the drawings, and a fly-wheel 34 is mounted on the opposite end of the rotor-shaft for the usual purpose.

The end-faces 35 of the piston 29 curve divergently from its inner face which contacts with the inner wall of the chamber 6 to its outer face which engages the opposite wall of the same, and when the parts are in their dead center, as shown in Fig. 2, the piston extending centrally in alignment with the centers of the two annular chambers, closes with its inner face, the port 20 and with its outer face the entrances to the lower section of the abutment chamber, while its curved end surfaces are engaged by the ends of the abutment 10.

The valve 13 is at the same time in the position in which its longitudinal slot 17 registers with the orifice 18 of the channel 19 so that when the rotor is moved in the direction of the arrow *a* in Fig. 2, the motive fluid contained in the steam chest 7, will be admitted into the space 36 between the abutment and the rear end-face of the piston as soon as the latter uncovers the port 20, and by its expansive force, drive the piston onward.

The abutment 10 moving in unison with the piston 20 in the direction of the arrow *c*, will remain in contact therewith until the end of the piston rearmost with relation to its direction of rotation has passed the adjacent entrance to the lower section of the abutment chamber, when the abutment entering the same will partition the piston-chamber at that point, as shown in Fig. 6 of the drawings.

The valve 13 which likewise moves in unison with the rotor in the direction of the arrow *d* will cover the port 18 only after the piston 29 has moved through an arc of approximately ninety degrees, when it is driven further onward by expansion of the body of motive fluid confined between its end surface and the abutment, until it passes the exhaust port 21 through which the motive fluid escapes from the piston chamber.

During the subsequent downward motion of the piston, the rotor is impelled by its own momentum and that of the fly-wheel 34, until the piston again passes the port 20 when a fresh supply of motive fluid is admitted in the space 36 and the above described operation is repeated.

In Fig. 5 of the drawings, the parts are shown in the position they occupy at the moment steam is admitted into the space between the piston and the abutment, Fig.

6 shows the parts when the steam-supply is shut off by the valve and the rotor is impelled by expansion of the motive fluid confined between the piston and the abutment, and Fig. 7 shows the parts at the moment the piston passes the exhaust port and the spent steam is discharged from the housing.

It will be understood that the location of the exhaust port may be changed to discharge the steam at an earlier or later period in the rotary movement of the piston, and that the efficiency of the engine may be increased by providing two pistons at diametrically opposite points on the rotor, in which case the gearing is changed to cause the abutment to make two complete revolutions while the piston makes one, and the valve is provided with two slots 17.

It will furthermore be observed that by reversing the exhaust and intake openings, the engine may be employed to operate as a pump for raising or circulating water or other fluid.

Having thus described my invention what I claim and desire to secure by Letters-Patent is:

1. A rotary engine comprising a housing having an annular piston-chamber and, in intersection therewith, an annular abutment-chamber, a rotor having a piston movably fitted between the circular walls of said piston chamber, the end faces of said piston diverging from the inner one of said walls to the other, and a segmental cylindrical abutment movable in said abutment-chamber and adapted to partition said piston chamber, the said end faces of the piston and the said abutment being formed and proportioned so that the longitudinal edges of the latter will move in engagement with the respective end surfaces of the piston while the latter passes the point of intersection of the two chambers.

2. A rotary engine comprising a housing having an annular piston chamber defined by its circumferential wall and a therewith concentric central portion, and in intersection with said chamber, an annular abutment chamber, said central portion having a valve seat in communication with the piston chamber, a rotor having a piston movable in the piston chamber, a rotary abutment in the abutment chamber adapted to periodically partition the piston chamber, and a rotary valve in said seat.

3. A rotary engine comprising a housing having an annular piston chamber defined by its circumferential wall and a therewith concentric central portion, and in intersection with said chamber, an annular abutment chamber, said central portion having a steam chest and a valve seat in communication with said chest and with the said piston chamber, a rotor having a piston movable in the piston chamber, a rotary abutment

ment in the abutment chamber adapted to periodically partition the piston chamber, and a rotary valve in said seat.

4. A rotary engine comprising a housing having an annular piston chamber defined by its circumferential wall and a therewith concentric central portion, and in intersection with said chamber, an annular abutment chamber, said central portion having 10 a valve seat in communication with the piston chamber, a rotor having a piston movable in the piston chamber, a rotary abutment in the abutment chamber adapted to periodically partition the piston chamber, 15 a rotary valve in said seat, and means for rotating said rotor, said abutment and said valve in unison.

5. A rotary engine comprising a housing having an annular piston chamber defined by its circumferential wall and a therewith concentric central portion, and in intersection with said chamber, an annular abutment chamber, said central portion having a valve 20 seat in communication with the piston chamber, a rotor having a piston movable in the piston chamber, a rotary abutment in the abutment chamber adapted to periodically partition the piston chamber, a rotary valve in said seat, and means for rotating said 25 rotor, said abutment and said valve in unison at equal rates of speed.

6. A rotary engine comprising a housing having an annular piston chamber defined by its circumferential wall and a therewith 35 concentric central portion, and in intersection with said chamber, an annular abutment chamber, said central portion having a valve seat in communication with a port in the piston chamber disposed intermediate 40 of the point of intersection of the abutment chamber therewith, a rotor having a piston movable in the piston chamber, a rotary abutment in the abutment chamber adapted to periodically partition the piston 45 chamber, and a rotary valve in said seat.

7. A rotary engine comprising a housing having an annular piston chamber, and in intersection therewith, an annular abutment chamber, a rotor having a piston movable in the piston chamber, and a rotary abutment in the abutment chamber adapted to periodically partition the piston chamber, the latter having an admission port in the 50 space between the points of intersection of the abutment chamber therewith, and an exhaust opening outside said space.

8. A rotary engine comprising a housing having an annular piston chamber defined by its circumferential wall and a therewith concentric central portion, and in intersection with said chamber, an annular abutment chamber, a head closing an end of said housing in spaced relation to said central portion, a rotor comprising a disk rotatably fitted between said head and said central portion, and a laterally projecting piston 60 movably fitted in said piston chamber, and a rotary abutment fitted in said abutment chamber and adapted to periodically partition the piston chamber.

9. A rotary engine comprising a housing having an annular piston chamber defined by its circumferential wall and a therewith concentric central portion, and in intersection with said chamber, an annular abutment chamber which opens in an end-surface of the said housing, a head closing the open end of said abutment chamber in spaced relation to the said end surface, a disk rotatably fitted between said head and 75 said surface and having a laterally extending segmental abutment fitted in said abutment chamber, a rotor having a piston movable in the piston chamber, and means for causing said rotor and said piston to rotate 80 in unison.

10. A rotary engine comprising a housing having an annular piston chamber defined by its circumferential wall, and a therewith concentric central portion, and in intersection with said chamber, an annular abutment chamber which opens in an end surface of said housing, a head closing the opposite end of said housing in spaced relation to said central portion, a rotor comprising a disk rotatably fitted between said head and said central portion and a laterally projecting piston movably fitted in said piston chamber, a head closing the open end of 90 said abutment chamber in spaced relation to the said end surface, a disk rotatably fitted between the last mentioned head and the said end surface and having a laterally extending segmental abutment fitted in said abutment chamber, and means for causing 95 said rotor and said disk to rotate in unison.

In testimony whereof I have affixed my signature in presence of two witnesses.
